Primary Examiner — Sharon S Oum(74) Attorney, Agent, or Firm — McGarry Bair PC(57) CLAIM

The ornamental design for a ceiling fan, as shown and described.

DESCRIPTION

FIG. 1 is a top perspective view of a ceiling fan, showing my new design;

FIG. 2 is a bottom perspective view thereof;

FIG. 3 is a top view thereof;

FIG. 4 is a bottom view thereof;

FIG. 5 is a front view thereof;

FIG. 6 is a rear side view thereof;

FIG. 7 is a right side view thereof; and,

FIG. 8 is a left view thereof.

The broken lines illustrate portions of the ceiling fan that form no part of the claimed design.

The ceiling fan blades are shown with a symbolic break in their length. The appearance of any portion of the ceiling fan blade between the break lines forms no part of the claimed design.
